Frank Liebenow; Justin P. Miller(57) **CLAIM**

The ornamental design for a smoke pod, as shown and described.

DESCRIPTION

FIG. 1 is a perspective view of a smoke pod showing our new design;

FIG. 2 is a front elevation view;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a cross sectional view.

The broken lines depicting bottom features of the smoke pod in FIG. 7 form no part of the claimed design. The broken lines depicting internal components in FIGS. 1 and 8 form no part of the claimed design.
